UNITED STATES PATENT OFFICE.

WALTER LLOYD, OF CHICAGO, ILLINOIS.

LOCK-UP FOR PRINTERS' FORMS.

SPECIFICATION forming part of Letters Patent No. 352,248, dated November 9, 1886.

Application filed May 1, 1886. Serial No. 200,822. (No model.)

To all whom it may concern:

Be it known that I, WALTER LLOYD, of Chicago, in the county of Cook and State of Illinois, have invented a new and Improved 5 Lock-Up for Printers' Forms, of which the following is a specification, reference being had to the annexed drawings, forming a part thereof, in which—

Figure 1 is a plan view of my improved 10 lock-up. Fig. 2 is a longitudinal section taken on line $x-x$ in Fig. 1. Fig. 3 is a detail view of one of the cross-bars.

Similar letters of reference indicate corresponding parts in the different figures of the 15 drawings.

The object of my invention is to provide means for quickly locking up forms in a chase and readily changing to forms of different sizes and proportions.

20 My invention consists in two bars slotted lengthwise, two cross-bars fitted to the slots of the longitudinal bars, the longitudinal and cross bars each being provided with two sets 25 of ratchet-teeth on their outer faces, each set of ratchet-teeth upon each bar projecting toward the center of the bar, and in the combination, with the set of toothed bars, of right-angled corner-blocks provided with ratchet-teeth for engaging the teeth of the bars, and 30 in an expansible corner-block adapted to one of the corners of the lock-up, for contracting on the form, the frame consisting of the bars.

The longitudinal bars A A', forming part 35 of the frame of the lock-up, are each provided with longitudinal slots a , extending nearly to their ends, and the ends of the bars A A' are slotted in the same direction, to receive a tongue, b , on the inner edge of the chase B. 40 The adjacent faces of the bars A A' are plane; but each bar is provided with two oppositely-arranged sets of ratchet-teeth, c , which pitch toward the center of the bar. In the slots a of the bars A A' are inserted the cross-bars 45 C C', whose ends are enlarged and slotted to receive the tongue b of the chase B. The adjacent faces of the bars C C' are plane, and their outer faces are provided with oppositely-arranged sets of ratchet-teeth, c' , similar to the ratchet-teeth of the bars A A'.

To three of the angles, between the bars A A' C C', are fitted triangular blocks D, having ratchet-teeth c'' on adjoining faces, which are at right angles to each other. The ratchet-teeth c'' of the blocks D are adapted to en-

gage the ratchet-teeth c of the bars A A' C C'. To the fourth angle, between the longitudinal and transverse bars is fitted an expansible triangular block, D', formed of the two sections d , provided with ratchet-teeth 60 c'' , and a wedge, e , inserted between the two sections d , and adapted to force the two sections apart.

The action of my improved lock-up is as follows: The form being placed in the opening E between the bars A A' C C', the bars are moved forward into contact with the sides of the form, when the triangular blocks D are placed between the bars, and the expansible block D' is placed in the fourth angle. 65 By pressing the wedge e between the block-sections d the block-sections are forced apart, carrying the bars A A' C C' against the end and side of the form, and these bars act as levers, with the blocks D as fulcrums. 70

While the chase B, provided with the tongue b , is used in connection with my improved lock-up on some presses the beds of which are perpendicular, it is not vital to its efficiency, as in the case of larger forms, or forms 80 worked on cylinder-presses, no chase will be required, as the form lies flat upon the bed of the press, and consequently the ends of the longitudinal bars A A' and the cross-bars C C' need not be slotted. 85

My improved lock-up presents the following advantages: It saves the time usually lost in sorting out the quoins, furniture, and side-sticks to lock up with, it saves the expense of these quoins, and it does away with the wooden 90 furniture and side-sticks commonly used.

Having thus described my invention, what I claim as new, and desire to secure by Letters Patent, is—

The combination of the longitudinally-slotted bars A A', each provided with sets of ratchet-teeth c , which are oppositely arranged with respect to each other, the transverse bars C C', received in the slots of the bars A, and provided with sets of ratchet-teeth c' , which are oppositely arranged with respect to each other, the triangular blocks D, provided with ratchet-teeth c'' , and the expansible block D', formed of sections d , having ratchet-teeth c'' , and a wedge, e , adapted 95 to force the sections d apart, substantially as herein shown and described. 100 105
